H. G. MILLARD.

DRESSMAKER'S PATTERN OUTFIT.
APPLICATION FILED JAN. 29, 1916.

1,313,496.

Patented Aug. 19, 1919.

3 SHEETS—SHEET 3.

FIG. C.

Inventor

Hannah G. Millard
By her Attorney

Kir, Page, Cooper & Hayward

UNITED STATES PATENT OFFICE.

HANNAH G. MILLARD, OF NEW YORK, N. Y., ASSIGNOR TO THE BUTTERICK PUBLISHING COMPANY, OF NEW YORK, N. Y., A CORPORATION OF NEW YORK.

DRESSMAKER'S PATTERN OUTFIT.

1,313,496.

Specification of Letters Patent. Patented Aug. 19, 1919.

Application filed January 29, 1916. Serial No. 75,128.

To all whom it may concern:

Be it known that I, HANNAH G. MILLARD, a citizen of the United States, residing at New York, in the county and State of New York, have invented certain new and useful Improvements in Dressmakers' Pattern Outfits, of which the following is a full, clear, and exact description.

As is well known, users of paper patterns for women's dresses frequently experience great difficulty not only in identifying the several pieces of the pattern, but also still greater difficulty in properly fitting together the pieces of the dress-goods after the latter have been cut out. So great is this trouble, especially in the case of complicated patterns, that users are often put to the inconvenience and annoyance of being compelled to send the pattern to the maker thereof to have the parts pinned together in the proper arrangement. This has also been a source of expense to the makers, and in some cases they have been obliged to maintain departments for conducting correspondence of this character and for personally instructing users of the patterns.

Various attempts have been made in the past to obviate the difficulty mentioned. For instance, it has been common practice to give on the envelop or package containing the pattern a picture of the completed garment, with numbers or other identifying marks applied to such parts as are shown in the picture. This scheme has been found to be of little or no value when the pattern is complicated and composed of numerous pieces; and even in the case of comparatively simple garments, many women who have no, or but slight, experience in dress-making, find small aid in the plan referred to. It has also been proposed to give a development of the pattern on a flat surface. A little reflection will make it clear that the correct method of constructing the garment cannot be given by this method.

I have accordingly been led to devise my present invention, which has for its object to provide an improved pattern outfit, comprising a paper pattern composed of a plurality of pieces or parts according to which the cloth or other material for the garment is to be cut, and an instruction chart or sheet, illustrating and explaining the use of the pattern pieces in such manner that the tyro can scarcely go astray but can begin the

putting together of the garment-pieces at the proper point and from there continue in the proper sequence of steps to the completion of the work in the easiest and quickest way. To this and other ends the invention consists in the novel features hereinafter described.

In carrying out my invention in the preferred manner I provide the pattern-pieces with identifying marks or characters, such as numerals formed by perforations in the paper, in the order or sequence in which the pieces are to be used in putting the garment together. Thus the piece to be used first is marked "1", the second "2", and so on. On the instruction sheet or chart (or on the envelop if the same is large enough for the purpose) I print a series of views illustrating in perspective the pattern or garment as it appears at successive stages of the work; and wherever it seems necessary or desirable, I apply to the figure words of instruction or explanation to aid the user in understanding the procedure. As stated above, the parts composing the pattern are marked, usually with numbers and preferably in the sequence of their use, and in the views on the instruction sheet the parts are marked correspondingly, so that the pieces can be readily identified. I also employ the usual explanatory marks in or on the pattern pieces, such as perforations and notches, to indicate the various meeting-edges, etc., and these marks appear also on the corresponding parts of the pattern or garment illustrated on the instruction sheet. The sheet may also contain figures illustrating finishing features of the work, as for example, making belts, making "French tacks", making "tailors' tacks", etc.

The embodiment thus briefly outlined is illustrated in the accompanying drawings, in which Figure A shows the several pieces composing a paper pattern, with numbers, dots (perforations), notches, and words of explanation: Fig. B shows one side of the instruction chart and Fig. C the other side. The views on the chart, designated Fig. 1, Fig. 2, Fig. 3, etc., represent, some in perspective, some in plan, and some partly in plan and partly in perspective, the appearance of the garment at various stages of its construction. Preferably the sequence of the views runs substantially from left to right, especially if they are

not designated by letters or numerals indicating the sequence. The parts shown in the views are marked with the numbers or characters used in the pattern, 5 to identify them with the corresponding pattern-pieces; and by preference these characters (for example the numerals 1, 2, 3, etc.,) are such as will indicate clearly the order in which the parts are put together, 10 or their relative positions in the garment. For instance, piece 1 goes next to piece 2, piece 3 next to 4, etc. It is to be understood, of course, that the user will study the chart before she begins to put the garment-pieces 15 together.

In the case of the particular pattern or garment illustrated (a skirt), it is seen at once from Fig. 1, illustrating the left-hand half of the foundation skirt, that the first 20 step is to assemble, in the manner shown in the figure, the two-garment pieces corresponding to pattern-pieces 1 and 2; the numerals 1 and 2, in the figure, representing perforations in the pattern pieces. The figure 25 also shows, as will be observed, needle-and-thread at the points where the pieces are to be basted and afterward sewed. At the right side of the figure are the words "Center front", to indicate that in the finished garment the adjacent edge is at the center of the front. At the top are the words "Leave center back seam open above V V for placket", and on the left edge, at the point indicated by the dotted arrow 30 leading from the words quoted, are seen the two notches above which the dressmaker is to leave open the seam with which she joins the next piece to piece 2. At the bottom the words "Basting seam and dart in 35 foundation skirt with V and °° (dots) matched" indicate that in basting the two pieces together the meeting-edges thereof are to be so arranged that the V's (notches cut in the cloth at the points where the pattern-pieces are notched) in one edge are 40 to match or register with those in the other, and that in the dart at the top of the skirt the seam is to be made on the line of the dots, the latter being made on the goods 45 by means of tailors' tacks or by chalking through the perforations in the pattern-piece.

As indicated by Figs. 2 and 3, the next steps are making the belt and sewing it to 50 the top of the skirt; the construction of the belt being shown in Fig. 2, while Fig. 3 gives a side view of the skirt in perspective (from the left) with the belt in place. Next, pieces Nos. 3 and 4 are selected and treated 55 as explained in the marginal instructions in Fig. 4, which shows the two pieces as they appear when ready to be assembled, and also illustrates the method of laying in the plaits and putting in the gathers. In Fig. 5, pieces 60 3, 4, 5 and 6 are shown, as assembled, with

marginal explanations stating how they are arranged, what positions certain edges are to occupy in the completed garment, and what is to be done to the three pieces to make them ready for joining to the complete foundation skirt, composed of two halves of which the left-hand half is shown in Figs. 1 and 3. 70

The next steps are illustrated in Figs. 6, 7, 8 and 9, which clearly show the positions 75 of the pieces already referred to, and others, and explain how their edges are to be matched, etc. Fig. 10 shows how to make the "French tacks" called for by Figs. 7 and 9, and Fig. 11 how to finish the placket. 80

The pattern treated in the foregoing is one that in the trade would be, and is, considered fairly complicated, and the proper construction and draping of the outer or drapery skirt are things that many, probably most, amateur dressmakers would find exceedingly difficult. But with the instruction sheet containing the figures described, the operation is so clearly explained that it can be thoroughly understood in all its details. This is evidenced by the fact that in connection with this pattern outfit (of which large numbers have been sold) notably few complaints or requests for explanation have been received, in comparison with the number received in connection with other, and even less difficult, patterns with which instruction sheets of this character were not furnished. 95

It is to be understood that the invention 100 is not limited to the specific embodiment herein illustrated and described, but can be embodied in other forms without departure from its spirit. For example, it will not usually be necessary to number the figures 105 on the chart, as in most cases the numerals, as 1, 2, 3, etc., or letters, as A, B, C, D, etc., on the pieces or parts shown, will be sufficient to indicate clearly the order in which the parts are to be put together. Moreover 110 in many cases it will not be necessary to illustrate so many stages of the work as are shown in the present instance; while in other cases even more stages may be illustrated, depending, in general, upon the complexity 115 of the pattern and the number and shapes of the pieces composing it.

The views or figures may be printed on one or both sides of the chart, and the latter 120 usually bears a number identifying it with the pattern for which it is designed. It may also bear an appropriate heading, such as "Illustrated instructions for making pattern No. —," and may have general instructions such as are common on instruction sheets, as for example the legends designated by a, b, on Figs. B and C, respectively. 125

What I claim is:

1. An instruction sheet or chart for users 130

of dressmakers' paper patterns, comprising a sheet or chart having a series of views or figures exhibiting a series of successive stages in the making of the garment; said 5 views or figures showing also the appearance of the individual parts or pieces as they are successively assembled and their relations to each other at the several stages and illustrating the operations by which the 10 stages represented are reached in making the garment.

2. An instruction sheet or chart for users of dressmakers' paper patterns, the sheet or chart having a plurality of views or figures illustrating in proper sequence the operations to be performed in making the garment, the views or figures showing different 15 stages of the work as the same progresses and exhibiting the arranging together of

the parts in the relations which they are 20 to have to each other in the finished garment.

3. A dressmakers' pattern outfit, comprising a paper pattern composed of a plurality of pieces marked with identifying characters, and an instruction sheet or chart having a plurality of views illustrating a plurality of successive stages of the work and the procedure to be followed to reach such stages, and indicating the order or sequence of steps to be followed in making the garment; the parts or pieces shown in the several views or figures being marked with characters identifying them with the corresponding pattern pieces. 25 30 35

In testimony whereof I hereunto affix my signature.

HANNAH G. MILLARD.
